UNITED STATES PATENT OFFICE.

CHARLES ZIEGLER, OF LIMOGES, FRANCE, ASSIGNOR TO THE J. POUYAT COMPANY, OF NEW YORK, N. Y., A CORPORATION OF NEW YORK.

DESIGN FOR A COVERED DISH OR SIMILAR ARTICLE.

40,551.

Specification for Design.

Patented Mar. 1, 1910.

Application filed September 22, 1909. Serial No. 519,099. Term of patent 7 years.

To all whom it may concern:

Be it known that I, CHARLES ZIEGLER, a citizen of the Republic of France, residing at Limoges, in France, have invented a new, original, and ornamental Design for a Covered Dish or Similar Article, of which the following is a specification, reference being had to the accompanying drawings, forming part thereof.

Figure 1 is a side elevation of a covered dish or similar article showing my design; and Fig. 2 is a plan view of the same.

I claim:

The ornamental design for a covered dish or similar article as shown.

CHARLES ZIEGLER.
